UNITED STATES PATENT OFFICE.

RICHARD W. GRAHAM, OF BERKELEY, CALIFORNIA.

AUTOMATIC HYDRAULIC CASING-JACK.

1,104,355.

Specification of Letters Patent. Patented July 21, 1914.

Application filed July 19, 1913. Serial No. 779,963.

To all whom it may concern:

Be it known that I, RICHARD W. GRAHAM, a citizen of the United States, residing at Berkeley, in the county of Alameda and State of California, have invented new and useful Improvements in Automatic Hydraulic Casing-Jacks, of which the following is a specification.

This invention relates to an automatic, hydraulic jack for oil well casings.

The object of the invention is to provide a simple, substantial, practical casing jack which is so constructed that it will automatically raise and lower the well casing while drilling operations or similar work is taking place, thus preventing the casing from "freezing" by keeping it moving continuously.

The invention consists of the parts and the construction and combination of parts as hereinafter more fully described and claimed, having reference to the accompanying drawings in which,—

Figure 1 is a side elevation of the jack partly in section. Fig. 2 is a side elevation showing the position of the valve operating mechanism. Fig. 3 is a side elevation partly in section, showing the application of the invention.

In drilling deep oil wells or the like it is found that the casing used in lining the well often becomes "frozen" or stuck within the well by cavings or foreign material becoming lodged against the casing. Sometimes the casing sticks when fishing for lost tools. In order to free the casing and keep it loose where it is desired to continue lowering or to remove the casing, it is necessary, under ordinary working conditions, where my invention is not used, to stop drilling operations and remove the tools from the well, after which it is required to use casing blocks to lift the casing, in order to free it before the tools may again be replaced and drilling resumed. It is also necessary to employ additional men to operate the ordinary casing jack now in use, in order to keep sufficient pressure on the jack to produce sufficiently heavy strain on the casing while jarring the casing loose.

The purpose of this invention is to provide a hydraulic casing jack which will automatically raise and lower the casing at certain timed intervals while drilling or similar operations are taking place through

the casing, thus eliminating the loss of time usually necessitated by the removal of the tools from the well in order to lift or jar the casing loose.

Referring to the drawings: A indicates an open-ended cylinder in which is reciprocally mounted a plunger 2, having a central opening 3, through which the well casing, indicated at 4, is adapted to extend. The lower end of the plunger is provided with a tubular extension 5, provided for the purpose of guiding the casing and plunger, and is packed against leakage, as at 6, in the lower end of the cylinder, and as at 7 in the upper end.

For the purpose of automatically admitting liquid under pressure to the cylinder to lift the plunger and to release same to lower the plunger at certain timed intervals, the following valve operating mechanism has been provided: 8 and 9 indicate inlet and outlet valves of any suitable design provided for the purpose of controlling the flow of liquid to and from the cylinder. Suitably mounted upon the stems of the valves are levers 10 and 11, the inner ends of which are slotted, as indicated at 12, for the purpose of forming a sliding connection between the levers and a pair of rods 13 and 14, slidably mounted in bearings 15 and 16, upon the outside of the cylinder.

Suitably secured upon the rods 13 and 14 are two pair of stops 15^a—16^a and 15^b—16^b, and slidably mounted between the rods is a bar 17, upon the lower end of which is mounted a projecting lug 18. The upper end of the bar 17 is secured to a plate 19, suitably secured, as at 20, in a groove formed on the outer surface of the upper end of the plunger. Movement of the plunger in either direction will thus be transmitted through the bar 17 and lug 18 to either lift or depress the rods 13 and 14, which is caused by the lug 18 being brought into contact alternately with the adjustable stops 15^a—16^a or 15^b—16^b, the downward movement of the plunger and connected bar 17 being transmitted through the lug 18 to stops 15^b and 16^b, moves the rods 13 and 14, with connected levers 10 and 11, into a position where the inlet valve 8 will be opened while the outlet valve 9 will be closed. Fluid under pressure from any suitable source may thus be admitted to the cylinder to lift the plunger in an upward direction, the speed or up-

ward movement of the plunger being limited by the amount of liquid admitted through the valve 8, this having previously been adjusted to the required speed.

5 The upward movement of the plunger will similarly cause the lug 18 eventually to engage with the upper adjustable stops 15^a—16^a and lift the rods 13 and 14, with connected levers 10 and 11, into position 10 where the inlet valve 8 will be closed while the outlet valve 9 will be opened. The liquid is thus permitted to escape and the plunger allowed to settle into the lowered position, when the cycle of operation will 15 again be repeated.

15 In operation when drilling below a string of casing, indicated at 4, or fishing for tools lost in the casing, the jack, generally indicated at B, is lowered over the upper end 20 of the casing into position where it will rest upon the surface timbers, indicated at C. A spider of any suitable description, indicated at D, is then slipped over the casing and lowered into position where it will rest 25 upon top of the plunger head, as indicated in Figs. 1 and 3. The inlet valve 8 is then connected with the pressure pump, or any suitable source of pressure, not here indicated, and liquid admitted to the cylinder. 30 Upward movement of the plunger 2, caused by the admission of fluid under pressure to the cylinder, will immediately cause the slips 21 within the spider to grip the casing, thus causing the casing to be lifted in 35 unison with the plunger. The plunger, spider and casing supported by same, will thus move upwardly in unison until the lug 18 engages with the upper adjustable stops 15^a—16^a which will immediately reverse the 40 movement of the plunger by closing the inlet valve and correspondingly opening the outlet valve. The plunger, spider and casing supported thereby, are thus permitted to settle until the movement of the plunger 45 is again reversed and the cycle of operation repeated. The speed of the plunger may be regulated by the opening of the valves 8 and 9 and the exact lift of same may be adjusted by raising or lowering of the stops 50 15^a—16^a and 15^b—16^b upon the rods 13 and 14. Drilling operations may thus be continued without interruption while the casing is being continuously lifted and lowered 55 within the well bore or fishing operations for lost tools may take place without any danger of "freezing" the casing while such operations are taking place.

By employing a jack constructed as here shown, practically 50% more work can be 60 obtained from the drill when compared with the old method of drilling where the operation of lifting the casing and drilling were intermittent. The jack here shown is neat, simple and compact in construction, prompt 65 and automatic in action, and takes less space

than similar jacks heretofore employed. The materials and finish of the several parts are such as experience and judgment of the manufacturer may dictate.

For the purpose of preventing the casing from being strained or parted by the jack, a suitable form of pressure gage, indicated at 25, has been provided. The gage may be direct connected with the jack or may be mounted on the pressure line in any convenient position, where it can always be observed by the operator. The operator can thus prevent any accidental parting of the casing by simply reducing the pressure before it reaches the danger mark.

Having thus described my invention, what I claim and desire to secure by Letters Patent, is:

1. A hydraulic casing jack comprising in combination, an open-ended cylinder, a plunger mounted in said cylinder having a central opening extending therethrough to permit it to slip over a casing, and means connected with the cylinder for admitting fluid under pressure to lift the plunger.

2. A hydraulic casing jack comprising in combination, an open-ended cylinder, a plunger mounted in said cylinder having a central opening extending therethrough to permit it to slip over a casing, exhaust and inlet pipes connected with the cylinder, valves on said pipes, and means for automatically opening and closing said valves to intermittently admit and release fluid to raise and lower the plunger.

3. A hydraulic casing jack comprising in combination, an open-ended cylinder, a plunger mounted in said cylinder having a central opening extending therethrough to permit it to slip over a casing, exhaust and inlet pipes connected with the cylinder, valves on said pipes, and means connected with the plunger for opening and closing said valves to intermittently admit and release fluid to raise and lower the plunger.

4. A hydraulic casing jack comprising in combination, an open-ended cylinder, a plunger mounted in said cylinder having a central opening extending therethrough to permit it to slip over a casing, and means connected with the cylinder for intermittently admitting and releasing fluid to raise and lower the plunger.

5. A hydraulic casing jack comprising in combination, an open-ended cylinder, a plunger mounted in said cylinder having a central opening extending therethrough to permit it to slip over a casing, and means for reciprocating the plunger.

6. A hydraulic casing jack comprising in combination, an open-ended cylinder, a plunger mounted in said cylinder having a central opening extending therethrough to permit it to slip over a casing, valves connected with the cylinder for admitting and

releasing fluid to raise and lower the plunger, a pair of rods slidably mounted on the cylinder, levers mounted on the valves connected with said rods, means operated by the plunger for lifting said rods, and means on said rods for adjusting the lift of the plunger.

7. A hydraulic casing jack comprising in combination, an open-ended cylinder, a plunger mounted in said cylinder having a central opening extending therethrough to permit it to slip over a casing, valves connected with the cylinder for admitting and releasing fluid to raise and lower the plunger, a pair of rods slidably mounted on the cylinder, levers mounted on the valves connected with said rods, stops adjustably mounted on the rods, a bar secured to the

plunger slidably mounted with relation to said rods, and a lug on the bar adapted to engage with the stops on the rods.

8. A casing jack comprising a cylinder, a hollow piston adapted to fit over a casing, said casing and piston inclosing an annular piston chamber, fluid connections with the cylinder, and means operated by the piston for controlling the inlet and outlet of fluid from the cylinder to actuate the piston.

In testimony whereof I have hereunto set my hand in the presence of two subscribing witnesses.

RICHARD W. GRAHAM.
